UNITED STATES PATENT OFFICE.

MARCUS I. MAYER AND GEORGE H. PHELPS, OF ST. LOUIS, MISSOURI.

DESIGN FOR A NOVELTY FIGURE.

58,446.

Specification for Design.

Patented July 19, 1921.

Application filed May 12, 1920. Serial No. 380,921. Term of patent 7 years.

To all whom it may concern:

Be it known that we, MARCUS I. MAYER and GEORGE H. PHELPS, citizens of the United States of America, residing in St. Louis, in the State of Missouri, have invented a new, original, and ornamental Design for Novelty Figures, of which the following is a specification, reference being had to the accompanying drawing, forming a part thereof, in which—

Fig. 2 is a side elevation thereof.

We claim:

The ornamental design for a novelty figure as shown.

In testimony whereof, we have signed our names to this specification.

MARCUS I. MAYER.
GEORGE H. PHELPS.
